UNITED STATES PATENT OFFICE

98,381

DESIGN FOR A NONREPEATING INDICATOR

Alfred R. Babcock, Chicago, Ill.

Application November 16, 1935, Serial No. 59,604

Term of patent 3½ years

To all whom it may concern:

Be it known that I, Alfred R. Babcock, a citizen of the United States, residing at Chicago, county of Cook, and State of Illinois, have invented a new, original, and ornamental Design for a Non-repeating Indicator, of which the following is a specification, reference being had to the accompanying drawing, forming a part thereof, in which:

Figure 1 is a front elevational view of a non-repeating indicator embodying the invention; Fig. 2, an end elevational view of the same; and Fig. 3, a top plan view of the same.

I claim:

The ornamental design for a nonrepeating indicator, as shown.

ALFRED R. BABCOCK.
